EXERCISING DEVICE

David E. Burns, Colfax, Wash.

Application December 11, 1941, Serial No. 422,569

1 Claim. (Cl. 272—58)

This invention relates to an exercising device and has for an object to provide a device of this character including a frame, a seat, and a front cross bar underneath which the user may hook his feet while seated upon the seat to permit of the body being bent backwardly and forwardly at the hips to simulate rowing a boat to the end that the muscles will be strengthened, as well as improved digestion and circulation greatly promoted.

A further object is to provide a device of this character having a seat adjustable longitudinally of the frame and accommodating the device to persons having long or short legs.

A further object is to provide a device of this character which will be formed of a few strong, simple and durable parts, which will be inexpensive to manufacture, and which will not easily get out of order.

With the above and other objects in view, the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming a part of this specification:

Figure 1 is a perspective view of an exerciser constructed in accordance with the invention and showing the same in use.

Figure 2 is a perspective view of the exerciser.

Figure 3 is a fragmentary bottom plan view showing the adjustable seat.

Figure 4 is a detail cross sectional view taken on the line 4—4 of Figure 3.

Referring now to the drawing in which like characters of reference designate similar parts in the various views, the exercising device comprises a frame 10 having side members each formed of a horizontal bottom bar 11, an upwardly and rearwardly inclined top bar 12, a U-shaped bar 13 connecting the front ends of the top and bottom bars, and a vertical bar 14 connecting the top and bottom bars near the rear ends. The rear ends of the bottom bars project beyond the rear ends of the top bars to prevent the device from pivoting upward on the rear end when in use.

An X-shaped brace member 15 connects together the rear ends of the side members. A front cross bar 16 connects together the front ends of the top bars 12. The frame constructed as above described may be formed of tubing, rods

or similar material, and preferably all joints are welded to provide a frame in a single integral piece throughout.

5 A seat 17, formed of plywood or other material, is provided on the bottom face with spaced longitudinal guide ribs 18 adapted to extend along the inner sides of the top bars 12 and form guides for holding the seat against lateral movement but permitting of the seat being slid longitudinally on the top bars of the frame to various adjusted positions. A pair of bolts 19 are engaged through the rear end of the seat and through the ribs 18 near the rear ends of the latter. A pair of longer bolts 20 are engaged through the seat and through the ribs near the front ends of the latter, these bolts being equipped with wing nuts 21.

20 A metal clamp bar 22 is disposed transversely across the ribs 18, see Figure 4, and is provided with openings to receive the front long bolts 20. The clamp bar 22 projects beyond the ribs 18 and when the wing nuts 21 are tightened, the clamp bar clamps the seat 17 firmly in adjusted position on the top bars 12 of the frame.

25 In use, the operator hooks his toes underneath the front cross bar 16, which consequently forms a foot rest or grip, and sits himself upon the seat, preferably with his arms folded so that his entire weight is supported without the use of the arms. Then the operator sways forwardly and backwardly, as shown by full lines and by dotted lines respectively, in Figure 1, to exercise the muscles of the legs, stomach and back, as in rowing a boat.

30 The seat 17 is adjusted longitudinally of the frame 10 by loosening the wing nuts 21 and moving the seat to the selected adjusted position, then tightening the wing nuts in order that operators of various heights, and consequently having long or short legs, may conveniently exercise with the device.

35 From the above description it is thought that the construction and operation of the invention will be fully understood without further explanation.

40 What is claimed is:

45 An exercising device comprising a pair of transversely spaced approximately U-shaped side sections, each of said sections including a longitudinal bottom bar having its front end curved arcuately upward and joining a top longitudinal bar, said top bar being disposed to assume an upwardly diverging relation from the front to the rear of the bottom bar and terminating short 50 of the latter, a vertical bar secured to and ex-

tending between said top and bottom longitudinal bars inwardly of the rear end of the former, an X-shaped vertical brace disposed transversely between and connecting said sections, a foot bar secured to and extending between the front end portions of the respective top bars and disposed at a height sufficient to slide the feet of a user thereunder, a flat seat forming member mounted transversely across the top bars and slideable longitudinally thereon, a pair of guide ribs fixed to the underside of the seat parallel

5 with and in close proximity to the top bars to prevent transverse displacement of the seat, a clamp bar extended transversely of the underside of the seat and top bars, a pair of bolts depending from said ribs and extending through openings in the clamp bar, and a wing nut fitted on the outer end of each of said bolts for releasably forcing the clamp bar into gripping engagement with the top bars.

DAVID E. BURNS.
